UNITED STATES PATENT OFFICE

DAVID SCHLESINGER, OF BROOKLYN, NEW YORK.

SHIRT.

1,117,525.

Specification of Letters Patent. Patented Nov. 17, 1914.

Application filed March 20, 1914. Serial No. 825,923.

To all whom it may concern:

Be it known that I, DAVID SCHLESINGER, a citizen of the United States, and residing in Brooklyn, county of Kings, and State of New York, have invented certain new and useful Improvements in Shirts, of which the following is a specification.

This invention relates to a shirt of novel construction, which effectively protects the body of the wearer, especially at the crotch, may be readily put on or taken off, and does not present an objectionable fullness that requires to be tucked in around the limbs.

In the accompanying drawing, Figure 1 is a perspective view of a shirt embodying my invention, showing the flap closed, and Fig. 2 a similar view of the lower part of the shirt, showing the flap open.

From the back of the shirt 10, there depends a centrally disposed flap 11, which is connected to the shirt-body, by means of a narrow neck 12. This neck is so constituted that it increases in fullness from the medial line 13, toward its right and left edges, so that ample material is here provided for fitting the crotch of the wearer. The entire body of the shirt is composed of but two parts or sections, which are connected along their entire length by a back seam. The neck 12 and flap 11, are made integral with the body of the shirt, each shirt section being made integral with one of the flap sections, while the back seam extends continuously through the neck, to the tip of the flap, so as to connect the sections thereof. In order to provide for the proper fit at the crotch, the edges of the flap which meet at the back seam, are below the neck 12, cut at an angle to the edges which meet above the neck, so that upon uniting the edges by means of the back seam, the required fullness is produced. The flap 11, is made substantially in the form of a spear-head, the converging sides of which are inwardly deflected toward their converging ends, to form a tip that joins the main portion of the flap at obtuse angles. In order to reinforce the flap, its sides are doubled as at 14, a button hole or similar fastening member being

formed within the doubled sections, at the tip as at 15, while two additional fastening members 16, are formed opposite the obtuse angles. At the front, the bottom of the shirt is cut away, the two diverging edges 17, forming an intervening triangular gap 55 which is adapted to be closed by flap 11. A pair of buttons or similar fastening members 18, are secured to the shirt front directly above the cut away section thereof, while a pair of additional buttons 19 are provided at each side of such section.

In use the shirt is put on in the usual manner, the flap 11 after being drawn forward, is turned up, and then the coacting fastening members 15, 18, and 16, 19 are closed so that the flap is secured in position. By doubling the number of fastening members 18, 19 in the manner described, the flap may be so adjusted as to fit snugly without causing any uncomfortable pressure. 70

It will be seen that the shirt constructed as described, can be put on or taken off in a very simple manner, that it effectively protects the body of the wearer and that by increasing the upper portions of the limbs, it is well adapted to be worn without drawers. 75

The invention may be applied to outer garments as well as to undergarments, and may be adapted for use by either men or women. 80

Claim.

A shirt having a body composed of two sections, each section terminating at its lower end into one section of an integral bipartite flap having an upper neck that increases in fullness toward its edges, the sections of the shirt body, as well as the sections of the flap being connected to each other by means of a common seam that extends along the back of the shirt continuously through the neck up to the tip of the flap, and means for detachably securing the flap to the shirt front. 85 90
